[57] CLAIM

The ornamental design for a chaise lounge, as shown and described.

DESCRIPTION

FIG. 1 is a perspective view of a chaise lounge showing my new design with the backrest in one of a number of possible positions;

FIG. 2 is a top plan view thereof;

FIG. 3 is a front elevational view thereof;

FIG. 4 is a right side elevational view thereof, the left side view being a mirror image of that shown; and,

FIG. 5 is a rear elevational view thereof.

The bottom surface of the chaise lounge is not part of the design sought to be patented and is therefore not shown. The design sought to be patented includes the backrest in any one of a number of possible positions.
